[57] CLAIM

The ornamental design for a micropipetting device, as shown.

DESCRIPTION

FIG. 1 is a front elevational view of a micropipetting device, showing my new design, the rear elevational view being substantially a mirror image thereof;

FIG. 2 is an elevational view of the right hand side shown in FIG. 1;

FIG. 3 is an elevational view of the left hand side shown in FIG. 1;

FIG. 4 is a top plan view; and,

FIG. 5 is a bottom plan view.
